UNITED STATES PATENT OFFICE.

FREDERICK W. LEESBERG, OF ST. LOUIS, MISSOURI.

SHANK-STIFFENER.

No. 892,064.

Specification of Letters Patent. Patented June 30, 1906.

Application filed September 5, 1906. Serial No. 333,396.

To all whom it may concern:

Be it known that I, FREDERICK W. LEESBERG, a citizen of the United States, and a resident of St. Louis, in the State of Missouri, have invented certain new and useful Improvements in Shank-Stiffeners, of which the following is a full, clear, and exact description, such as will enable those skilled in the art to which it appertains to make and use the same, reference being had to the accompanying drawing, forming a part of this specification.

The invention relates to improvements in shank-stiffeners used in boots and shoes.

It has for its object the provision of a device that will accurately conform to the shape of the arch of the foot and which will meet both the vertical and lateral strains exerted by the pressure of the foot in walking.

It consists in the novel construction hereinafter fully described, pointed out in the appended claims, and illustrated in the accompanying drawings.

In the drawings, in which similar letters of reference designate corresponding parts, Figure 1 is a plan view of a device embodying the invention. Fig. 2 is a side elevation. Fig. 3 is a sectional view on the line 3—3 of Fig. 1.

The stiffener is formed of a plate of thin spring metal comprising two members, A and B, respectively, which are joined by the central integral connection C. The two members are separated at their ends by the wedge-shaped openings D which permit them to move independently of each other to a considerable extent. The stiffener is bent transversely along its median line extending between the apexes of the openings D, as at E, to form an obtuse angle between the two members. The latter are bent longitudinally to different degrees of curvature, the member A being comparatively shallow and the member B comparatively deep.

The shallow curvature of the member A fits the comparatively low arch of the outer side of the foot and the deep curvature of the member B fits the comparatively higher arch on the inner side of the foot. In its position in the shank of the shoe the member A is horizontal transversely to adapt it to the flat outer part of the foot and the member B is bent upwardly in a transverse direction to

conform to the inclination of the arch on the inner side of the foot. Also the member A is of such width as to accommodate the flat outer part of the foot and the member B, which is wider, is adapted to the width of the arch on the inner side of the foot. The outer edge of the member A is straight to meet the straight outer edge of the foot and the outer edge of the other member is curved to follow the curved inner side of the foot. When in position the member A springs in a vertical direction only to support the flat outer part of the foot in the direction in which the pressure is applied, and the member B springs both vertically and laterally to take up the pressure exerted by the inner arched part of the foot.

Having thus described my invention, what I claim and desire to secure by Letters-Patent is,

1. A shank-stiffener formed of a plate of thin spring metal comprising two longitudinally curved members joined by a central integral connection, said stiffener being bent along its median line to form an obtuse angle between the members.

2. A shank-stiffener formed of a plate of thin spring metal comprising two members joined by a central integral connection and separated at their ends by wedge-shaped openings, said stiffener being bent transversely along its median line to form an obtuse angle between the members, and one of said members having a comparatively shallow longitudinal curvature and the other member having a comparatively deep longitudinal curvature.

3. A shank-stiffener formed of a plate of thin spring metal comprising two members joined by a central integral connection and separated at their ends by wedge-shaped openings, said stiffener being bent transversely along its median line to form an obtuse angle between the members, and one of said members having a straight outer edge and a comparatively shallow longitudinal curvature and the other member having a curved outer edge and a comparatively deep longitudinal curvature.

In testimony whereof I hereunto affix my signature in the presence of two witnesses.

FRED. W. LEESBERG.
